VEHICLE OF THE TRICYCLE OR VELOCI-
PEDE TYPEMayo E. Roe, Elyria, and Wilbur Henry Adams,
Cleveland, Ohio, assignors to The Colson Cor-
poration, Elyria, Ohio, a corporation of Ohio

Application August 3, 1936, Serial No. 94,018

8 Claims. (Cl. 280—274)

This invention relates to vehicles of the tricycle or velocipede type.

Among the objects of the invention are to provide:

- 5 An improved vehicle of the class referred to;
- A vehicle of the class referred to having an improved frame or body construction;
- An improved frame or body construction for vehicles of the class referred to.
- 10 Other objects will be apparent to those skilled in the art to which our invention appertains.
- 15 Fig. 1 is a side elevational perspective view of a velocipede embodying our invention;
- Fig. 2 is a top plan view of the velocipede of Fig. 1;
- Fig. 3 is a view to a larger scale, substantially 20 full scale, of a part of Fig. 2 with parts broken away and parts in section for clearness;
- Fig. 4 is a fragmentary side elevational view taken from the plane 4—4 of Fig. 3;
- Fig. 5 is a view to an enlarged scale, substantially 25 full size, of a part of the head construction of the vehicle of Fig. 1, the parts being broken away and in section to illustrate the interior construction thereof;
- Fig. 6 is a bottom plan view of the parts of 30 Fig. 5;
- Fig. 7 is a fragmentary sectional view taken from the plane 7—7 of Fig. 5;
- Fig. 8 is a view illustrating a frame or body 35 construction for vehicles, such as that illustrated in Fig. 1, and embodying our invention in modified form; the view being in perspective and from the same viewpoint as that of Fig. 1, other parts of the vehicle being omitted to simplify the drawings;
- 40 Fig. 9 is a top plan view to an enlarged scale, substantially full size of some of the parts of Fig. 8, the view being partly in section and partly broken away and being considered as taken in the direction of the arrow 9 of Fig. 8;
- 45 Fig. 10 is a view taken from the plane 10—10 of Fig. 9.

Referring to the drawings, we have shown at 1 the vehicle front wheel, rotatable on bearings on a fork 2 the fork having a castering bearing 50 at 3, to be more fully described, and handle-bars 4 connected thereto, within reach of a rider on the seat 5 supported on a frame shown generally at 6, the frame at the rearward portion of the vehicle being supported on rear wheels 55 7—7.

The parts referred to constitute no essential part of our invention and may be variously constructed; except as to the frame 6 and its castering bearing 3 and the connection between the frame and the axles of the wheels 7 wherein our invention resides and which will now be described more fully.

The castering bearing referred to generally by the reference character 3 comprises in the preferred embodiment a metal tube 8, preferably 10 relatively thick walled, having pressed into opposite ends thereof, bearing bushings 9—9 provided with finish flanges 10—10 overlapping the ends of tube 8; and it is within the bores of the bushings 9—9 that the stem of the fork 2 above 15 referred to has castering bearing.

The frame proper, referred to generally at 6 in Figs. 1 and 2, comprises a pair of metal tubes 11—11 abutted upon and welded to the tube 8 at their forward ends, (see also Figs. 5 and 6) 20 the tube 8 being shown in Fig. 6 without the bushings 9—9 for clearness. The tubes 11—11 extend rearwardly from the tube 8 and diverge from each other as plainly shown in Figs. 2 and 6. A metal bracing member in the form of a 25 gusset 12 preferably triangular in form is welded along one edge as at 13 to the tube outer wall 8, extends upwardly between the adjacent tubes 11—11 and is welded likewise thereto. By this construction the front end portions of the tubes 30 11—11, the bearing tube 8, and the brace 12, are all integrally welded together.

A saddle post socket 14 is formed from a piece of thick walled metal tubing and opposite sides thereof are grooved as at 15—15, generally to 35 the radius of the tubing 11—11 and the tubes 11—11 are laid in the grooves 15—15 and welded to the tubing piece 14; and a set screw 16 may be provided through a wall of the socket 14 to clamp the saddle post 17, see Fig. 1, therein in 40 suitably vertically adjusted position.

A channel element 18 of sheet metal, downwardly open is placed over the structure thus far described. The web 19 of the channel rests upon the upper side of the tubes 11—11, the flanges 45 20—20 of the channel lie along the sides of the tubes 11—11 and the forward end edges 21—21 of the channel flanges lie upon the side of the tube 8 and are welded thereto. The channel flanges are also welded for example, as at 22—22, 50 to the tubes 11—11; and the channel flanges 20—20 are preferably of greater vertical depth adjacent to the tube 8 than at their rearward end portions.

When the vehicle is in use, and the front wheel 55

1 rests on the ground and load is applied on the seat 5, forces are developed in the structure thus far described which tend to bend the tube 8 off from the ends of the tubes 11-11 and which tend 5 to twist with torsional force, the forward ends of the tubes 11-11, and these forces are resisted with the maximum of resistance for the minimum of material by the structure above described; and the channel 18 besides absorbing torsional 10 and bending forces covers the parts in a manner to render the construction pleasing in appearance.

The tubes 11-11 diverge rearwardly from the head construction just described and extend rearwardly and downwardly therefrom and at their lower end portions 23-23 are bent so as to extend forwardly again, thus providing at about the level of the axis of the rear wheels 7-7, substantially straight horizontal forwardly extending 20 portions 24-24 spaced apart transversely.

As shown in Figs. 3 and 4, the ends 24-24 of the tubes 11-11 have inserted into their ends turned solid metal pieces 25-25 supporting opposite ends of a wheel axle 26. The axle preferably has at opposite ends thereof reduced diameter portions 27-27 which are fitted into suitable transverse bores in the pieces 25-25 and outwardly of the said pieces has reduced diameter portions 28-28 upon which the wheels 7 30 or bearings thereof are mounted, the portions 28 having threaded ends 29-29 for retaining nuts.

Forwardly beyond the axle 26 the pieces 25 are joined by a transverse piece of metal tubing 30 and rearwardly thereof the tubes 11-11 are joined by a transverse piece of tubing 31, the tubing 30 and 31 and the axle 27 all being preferably of substantially the same diameter and disposed in substantially a horizontal plane thus providing a platform upon which a rider may stand.

40 The parts 26, 30, 31 and 11-11 just described are joined together preferably by welding to provide smooth rounded joint corners and edges therebetween as illustrated in the lower half of Fig. 3. The parts 30 and 31, as described, also 45 perform the dual function of rendering the frame at the rearward wheel supporting end rigid to maintain the wheels 7-7 in forward and rearward alignment.

By the foregoing described construction a 50 rigid but light frame or body is provided for vehicles of this class.

In Figs. 8, 9 and 10 is illustrated a modification. In this form the forward head construction 32 55 may be the same as that more completely described above; the rearwardly extending frame tubes 11a-11a in this form however do not diverge as much as in the first described form and at their lower ends have forwardly extending portions 24a-24a which are secured to a generally oval frame 33.

The frame 33 is preferably made from a tube 35 bent into oval form. An axle bar 36 extends longitudinally of the frame 33, having reduced diameter wheel bearing supporting axle portions 60 65 37-37. The axle bar 36 is preferably secured to the frame 33 by laying the axle portions 37-37 in groove 38 in the ends of the oval frame 33 and rigidly joining the axle bar to the frame by welding as at 39 which welding also restores the 70 strength to the tube which was reduced by the notches 38.

The end portions 24a-24a of the frame tube, above referred to, abut upon and are welded to the axle bar 36 as at 40-40 and the two ends of 75 the tube from which the oval frame 33 is formed,

abut upon and are welded as at 41 to the outer lateral sides of the portions 24a-24a. A connecting piece of tubing 42 is inserted between the portions 24a-24a of the frame tube thus completing the oval configuration of the frame and strengthening the attachment of the frame and the frame tube to each other.

The oval 33 and its connected parts provide a rigid grating or platform which not only rigidly positions the rear wheels 7-7 on their axle portions 37-37 but as in the first above described form provide a platform upon which a rider may stand while straddling the frame tubes 11a-11a.

Our invention is not limited to exact details of construction shown and described. Two forms of frame are shown and other changes and modifications may be made within the scope and spirit of our invention and without sacrificing its advantages and within the scope of the appended claims.

We claim:

1. In a vehicle of the class described, a front head construction, a pair of tubular body elements secured at forward end portions to the head construction and extending rearwardly and divergingly downwardly therefrom and at their rear end portions extending forwardly, a frame comprising a plurality of transverse members rigidly welded together and welded to the said rear end portions of the tubular body elements and a pair 30 of aligned rear wheel axles extending oppositely from the frame and supported thereby.

2. In a vehicle of the class described, a front head construction, a pair of tubular body elements secured at forward end portions to the head construction and extending rearwardly and divergingly downwardly therefrom and at their rear end portions extending forwardly, a frame comprising a plurality of transverse members, disposed substantially in a horizontal plane, 40 rigidly welded together and welded to the said rear end portions of the tubular body elements, and a pair of aligned rear wheel axles extending oppositely from the frame and supported thereby.

3. In a vehicle of the class described, a front head construction, a plurality of elongated body elements secured at forward end portions to the head construction and extending rearwardly and divergingly downwardly therefrom and at their rear end portions extending forwardly, a frame 50 comprising a plurality of transverse members rigidly connected together and rigidly connected to the said rear end portions of the elongated body elements and a pair of aligned rear wheel bearing elements extending oppositely from the 55 frame and supported thereby.

4. In a vehicle of the type described, a front head construction, a pair of elongated body elements secured at forward end portions to the head construction and extending rearwardly and 60 downwardly therefrom and at their rear end portions being laterally spaced apart and extending forwardly, a supplemental frame comprising a plurality of transverse members disposed substantially in a horizontal plane rigidly connected 65 together and rigidly connected to the said rear end portions of the elongated body elements, and a pair of aligned rear wheel bearings secured to laterally opposite portions of the frame.

5. In a vehicle of the class described, a head 70 construction having a castering front wheel mounted thereon, a frame comprising a plurality of bent elements secured at one end to the head construction and extending rearwardly downwardly therefrom and terminating in forwardly 75

extending end portions spaced apart laterally, a supplemental frame rigidly connected to the forwardly extending end portions and provided with opposite laterally extending aligned rear wheel bearing elements.

5. In a vehicle of the class described, a head construction having a castering front wheel mounted thereon, a frame comprising a plurality of bent elements secured at one end to the head construction and extending rearwardly downwardly therefrom and terminating in forwardly extending end portions spaced apart laterally, a supplemental frame comprising a plurality of transversely extending frame elements rigidly connected to the forwardly extending end portions and provided with opposite laterally extending aligned rear wheel bearing elements.

6. In a vehicle of the class described, a front head construction, an elongated body element secured at its forward end portion to the head con-

struction and extending rearwardly and divergently downwardly therefrom and at its rear end portion extending forwardly, a frame rigidly connected to the said rear end portion of the elongated body element, and a pair of aligned rear wheel bearing elements extending oppositely from the frame and supported thereby.

7. In a vehicle of the class described, a head construction having a castering front wheel thereon, a frame secured at one end to the head construction and extending rearwardly downwardly therefrom and terminating in forwardly extending end portions spaced apart laterally, a supplemental frame rigidly connected to the forwardly extending end portions and provided with opposite laterally extending aligned rear wheel bearing elements.
